UNITED STATES PATENT OFFICE.

WILLIAM H. LAUDE AND FREDERICK PULESTON, OF MONTICELLO, IOWA.

NECKTIE-FASTENER.

1,094,795.

Specification of Letters Patent. Patented Apr. 28, 1914.

Application filed March 12, 1913. Serial No. 753,853.

To all whom it may concern:

Be it known that we, WILLIAM H. LAUDE and FREDERICK PULESTON, citizens of the United States, residing at Monticello, in the county of Jones and State of Iowa, have invented certain new and useful Improvements in Necktie-Fasteners; and we do hereby declare the following to be a full, clear, and exact description of the invention, such as will enable others skilled in the art to which it appertains to make and use the same.

This invention relates to necktie fasteners, and it more particularly relates to fasteners for bow ties.

The prime object of the invention is to provide an improved form of tie fastener which may be quickly and easily applied for securing the tie in place on an ordinary turn-down collar, being also applicable to standing collars.

Another object of the invention is to provide a fastener of this character which may be quickly and easily applied to any size or style of bow-tie.

Another object is to provide for protecting the stitches by which the fastener is secured to the bow-tie, so that said stitches cannot be cut or worn by contact with the collar or other object.

Another object of the invention is to provide a fastener of this character which will efficiently hold onto the collar and retain its adjusted position thereon.

Another object is to provide a fastener of this character by means of which the tie is held in proper shape, so as to present a graceful appearance at all times.

A further object is to provide a device of this character which is simple of construction and comparatively inexpensive to manufacture.

Other objects and advantages will be recited hereinafter and in the claims.

In the accompanying drawings, which supplement this specification, Figure 1 is a rear elevation view of a tie having our improved fastener applied thereto. Fig. 2 is a top plan view, and, Fig. 3 is a vertical sectional view through the middle of the fastener.

In these drawings, in which similar reference characters correspond to similar parts throughout the several views, the tie, which forms no part of the present invention, is illustrated for the purpose of showing the application of our invention, and is design-

nated by the numeral 5. The tie holder consists of three elements 6, 7 and 8 respectively. The element 6 is preferably stamped from springy sheet metal, such as steel, brass, or some suitable alloy, and this plate or spring constitutes the base member, being formed with apertures 9 through which stitches of thread 10 are passed, for securing the tie or bow thereto. The base 6 is also provided with apertures 11 which are preferably semicircular and are intersected by the median line of the base. These apertures are preferably adjacent to the respective top and bottom edges of the base and are separated by a bridge 12, the sides of which latter are parallel with said upper and lower edges of the base. This plate is also provided with grooves 13, extending from the top edge to the bottom edge and communicating with the apertures 9. These grooves or depressions constitute thread seats, while the adjacent shoulders or ridges 14 constitute thread protecting means, since obviously, the collar of the wearer is held out of contact with the threads or stitches 10 by means of said shoulders.

The spring or clamp element 7 may also be stamped from any suitable kind of sheet metal, and it may be either of the same kind or of a different kind of metal from that from which the plate 6 is formed. This plate is formed with apertures 15 which are intersected by its median line and which are of semicircular shape, being of the same size of and registering with the apertures 11. This plate is formed with a bridge 16 between the apertures, said bridge registering with the bridge 12 and being clamped snugly thereagainst by means of a clamp or staple 8. Obviously, this staple must be of ductile material, so that its opposite sides 18 may be passed through the apertures 11 and 15 and the ends 19 thereof may be bent inward, so that they lie flat upon the bridge 16. In practice, the width of the bridges 16 and of the sides or tongues 18 should be substantially equal, so that the plates or spring elements 6 and 7 are held in perfect alignment thereby; but, for the purpose of lucidly illustrating the device, the sizes of these apertures have been exaggerated.

At opposite sides of the apertures 15, and equidistant therefrom and from said medial line, the member 7 is provided with shoulders or ridges 20, which are evenly curved, and extend from the bottom to the top of

said plate 7, so as to protect the collar from contact with the relatively sharp edges of the element 19. Between these ridges 20, and communicating with the apertures 15 5 is a groove or recess 21, which provides sufficient space for the clenched ends 19 and also for the end of the collar-button (not shown) between or under said clenched ends. The opposite ends 22 are preferably curved 10 somewhat abruptly away from the element 6, so as to provide a relatively wide mouth or V-shaped notch 23, while the major portion of each half or wing of the member 7 lies snugly against the element 6, when not 15 in use, and in parallel relation thereto when applied to a collar, so as to present an extensive bearing surface upon each side of the collar, for holding with the maximum security.

20. In applying a tie which is fitted with this improved tie-holder, it is only necessary to place one of the V-shaped notches 23 against one of the forward edges of the collar and move the tie-holder laterally until the collar 25 has entered between the adjacent wings of the elements 6 and 7, and the said edge of the collar lies adjacent to the bridge 16, whereupon, the other front edge of the collar is pulled laterally sufficiently to allow it 30 to enter the other V-shaped notch and to be slid between the other pair of adjacent wings of the spring elements 6 and 7. It only remains now to raise or lower the holder, relative to the collar, until the collar-button is seated between or below the elements 19; but, obviously, it is not essential that the collar-button shall lie within the groove or collar-button seat, for the frictional contact of the spring elements 6 and 35 7 will ordinarily hold the tie in proper position independently of the collar-button, although, the notch 21 is useful for co-acting with the collar-button in determining whether the tie is properly applied in central 40 position or not. While we have described this tie-holder in connection with a bow-tie, it will be understood that we contem- 45

plate using this tie-holder on all forms of neck wear to which it may be applicable.

It is obvious that we have provided a tie-holder of this character which is fully capable of attaining the foregoing objects in a thoroughly practical and efficient manner.

We do not limit our invention to the exact details of construction, combination and arrangement of parts as herewith illustrated and described, but our invention may only be limited by a reasonable interpretation of the claims.

We claim:

1. The herein described tie-holder comprising a base plate adapted to be secured to a tie, a spring clamp element bent at its central portion to form a medial groove and spaced transverse shoulders adjacent said groove, one on each side thereof, and a staple extending through said base plate and having its ends bent into said groove and spaced from the ends thereof, whereby said ends may co-act with the portions of the shoulders lying between the ends and the end of the groove, in centering and retaining the tie-holder on a collar button.

2. The herein described tie holder comprising a base plate adapted to be secured to a tie, a spring clamp element bent at its central portion to form a medial groove, and spaced transverse shoulders adjacent said groove one on each side thereof, and connecting means between said base plate and 75 spring clamp element, said connecting means extending into said groove and adapted to co-act with the portions of the shoulders lying between the connecting means and the ends of the groove in centering and 80 retaining the tie holder on a collar button.

In testimony whereof we have signed our names to this specification in the presence of two subscribing witnesses.

WILLIAM H. LAUDE.
FREDERICK PULESTON.
